UNITED STATES PATENT OFFICE.

GEORGES MASSIP, OF LEVALLOIS-PERRET, FRANCE.

ELECTRIC FURNACE.

1,080,840.

Specification of Letters Patent.

Patented Dec. 9, 1913.

Application filed August 21, 1912. Serial No. 716,263.

To all whom it may concern:

Be it known that I, GEORGES MASSIP, a citizen of the French Republic, and resident of Levallois-Perret, France, have invented a certain new and useful Electric Furnace, of which the following is a full, clear, and exact specification.

This invention relates to electric furnaces such as are used in the manufacture of steel or iron alloys, free of carbon, and more particularly to tilting furnaces of this kind in which the walls of the furnace or crucible only become conductors at a high temperature. This high temperature is obtained by means of an auxiliary or starting arc.

According to the invention, the act of tilting the furnace or crucible brings the poles of the auxiliary arc into operative position and when the walls reach the necessary temperature, the furnace is restored to its normal position and the main or proper poles become operative.

The invention is illustrated somewhat diagrammatically in the accompanying drawings in which:

Figure 1 is a section of the furnace in its ordinary or normal position. Fig. 2 is a view showing the furnace tilted, to effect the preliminary heating.

In carrying the invention into effect according to the form illustrated, the walls of the furnace or crucible are made of a heat resisting material which does not give up carbon to the metal therein and which in consequence is only a conductor of electricity at higher temperatures.

This furnace rests on a metal plate *b*, which also forms the conductor or terminal for the lower electrode. The upper electrode is movable independently of the furnace and consists of a carbon *c*.

When the parts are in the position shown in Fig. 1, there is no arc formed even when the carbon *c* is lowered into the furnace. Opposite the outlet spout, I arrange an auxiliary metal electrode *d*, to which current is led by a bridge connection *e*. This auxiliary metal pole *d* cannot become operative over the large gap formed when the parts are as shown in Fig. 1, and it has no effect on the action when the furnace is heated up and in normal position. To start the furnace the gap between the poles *c* and *d* is reduced by tilting it about *o*, as an axis, *o*, being conveniently the center of the opening of the

roof. The opening at the top through which the carbon *c* passes is suitably shaped to permit of this tilting without interfering with the vertical position of the carbon. In the tilted position, the arc is formed between the pole *d* and carbon *c*, and this continues until the walls of the furnace *a* reach the requisite temperature to make them conductors of electricity. When this temperature is attained, the furnace is tilted back into the position shown in Fig. 1. The bridge connection *e* may then be opened to break current and the entire operation will proceed between the carbon *c* and the walls to which latter current is supplied by the metal terminal *b*.

Having now fully described my invention, what I claim is:

1. A tilting electric furnace of the character described, comprising a roof provided with an opening for the passage of an electrode and for allowing a tilting of the furnace about said opening as a center; a second electrode at the bottom of the furnace, means embedded in the furnace walls for forming an auxiliary arc with said first electrode for heating the furnace walls and making the same electrically conductive, and means for producing an arc between said first and second electrode through the charge and the furnace wall upon the return of the furnace into its normal position.

2. In a tilting electric furnace or crucible having walls of a refractory material which is a non-conductor of electricity when cold, a stationary electrode at the bottom of the furnace, a movable electrode passing through an opening in the roof of the furnace allowing a tilting of the furnace around said electrode without displacing the same, and an auxiliary electrode in the side wall of the furnace for forming an arc with said movable electrode during the tilting of the furnace for heating the walls of the furnace to the requisite temperature for making them conductors of electricity after the furnace has been swung into its normal, non-tilted position.

3. In a tilting electric furnace or crucible having walls of a refractory material which is a non-conductor of electricity when cold, a metal plate upon which the bottom of the furnace rests forming the lower electrode, a carbon electrode passing through an opening in the roof of the furnace allowing a

tilting of the same about said opening as a center, an auxiliary metal electrode in the side wall of the furnace opposite the spout thereof, for forming an arc with said movable carbon electrode during the tilting of the furnace for heating the walls of the same to the requisite temperature for making them conductors of electricity when the

furnace has been tilted back into its normal position.

In testimony whereof I affix my signature in presence of two witnesses.

GEORGES MASSIP.
